AUTOMATIC PAPER OR FOIL BREAK STOP

William M. Robinson, Fairhaven, Mass., assignor
to Cornell-Dubilier Electric Corporation, South
Plainfield, N. J., a corporation of Delaware

Application December 18, 1947, Serial No. 792,493

4 Claims. (Cl. 242—57)

1

This invention relates to a machine for winding sheets of paper and metallized foil into a condenser roll, each roll comprising metallic foils separated by numerous thin strips of dielectric paper. A number of thin strips are used for separating the foils, thereby obtaining electric characteristics better than would be obtained by the use of a single thick insulating strip. By employing multiple sheets or strips, individual faults in any sheet, such as conducting particles, pin-holes and the like are covered by other sheets, thus isolating the imperfections.

In practice the greater the number of insulating strips, the higher is the voltage at which the condenser can be operated.

In order to simplify terminology the various layers forming the condenser roll will hereafter be referred to simply as paper strips or sheets.

As the thicknesses of the strips are decreased their mechanical strength is decreased, consequently in the manufacture of condensers employing very thin dielectric sheets by the customary methods of manufacture, the tension applied to the sheets during the winding of the condenser will also have to be reduced. This leads to the production of condensers having somewhat erratic capacity because of non-uniformity of the spacing between the sheets, due to insufficient tension. Furthermore, the breaking of the mechanically weak sheets leads to rejections of imperfect condensers. It is impractical to visually check the rolls of condenser strips during the winding operation to make sure that strips from all of the supply rolls are being wound into the condenser.

The above trouble is of lesser importance when using a hand winding machine, where an operator is on the job to remove finished windings from the machine and thus may be able to determine by the actual size and feel of the product whether any layers of insulating paper are missing, but this is not true of automatic winding machines, one example of which is shown in Weiss Patent No. 2,384,983.

The present invention provides for automatically stopping the machine and/or indicate by visual or audible signal when any strip is broken during the winding operation. Repair of the break can then be made and the machine again set in motion.

The invention also puts the entire control of the machine and the stopping circuit under the control of the operator, so that the operator can continue the winding, stop and make repairs and then continue the winding independent of the stopping mechanism or stopping circuit.

In the drawings:

Fig. 1 shows a device which makes the electrical contact to stop the machine when a break occurs;

Fig. 2 is a side view of a machine which illustrates an application of the invention;

2

Fig. 3 is a detailed view of a portion of Fig. 2 which shows some of the parts in cross-section; and

Fig. 4 is a schematic wiring diagram of the invention.

Each of the many strips 14 is led over a guide bar 15 (Fig. 1) and thence to mandrel 18 of the winding machine (Fig. 2). A conventional device, not shown, maintains the strips at proper tension.

Mounted on each bar 15 is a ball bearing collar 16. Projecting radially from collar 16 is a rod L having a portion bent 90 degrees and passing underneath strip 14 and urged against the under surface thereof by a counterweight in the form of a bar K projecting from the opposite side of collar 16. Should a strip 14 break (with consequent decrease in its tension) counterweight K will fall or be pulled down by a spring 17, raising rod L against insulated contact J, thus closing a control circuit and giving a signal if desired.

Operation of winding mandrel 18 may be understood from Figs. 2 and 3. Pulley 20, freely rotatable on shaft 19, is driven continuously by a round belt B and may be pressed, through resilient disc 21, into driving engagement with a drum D which is keyed to the shaft by pin 47, thus rotating mandrel 18 through gears 22 and 23. A brake band E is provided around drum D. The band E is operated by solenoid 38, shown in Fig. 4, in the manner described below.

Pulley 20 is urged into engagement with drum D by means of a rotatable cap 25 on the end of an adjusting screw 24 threaded through the top of the vertical arm of a bell crank 26 pivoted at 27 and having on the end of its horizontal arm a friction or brake pad 28 normally held against the rim of drum D by a spring 29.

A chain 30 attached to the horizontal arm of bell crank 26 leads to a foot pedal P. When a slight pull is exerted on chain 30 brake pad 28 is moved out of engagement with the drum D, as in Fig. 3. Simultaneously, the vertical arm of the bell crank 26 urges rotatable cap 25 against the projecting hub of pulley 20 thus putting just enough pressure on disc 21 to drum D, shaft 19, and mandrel 18 to rotate slowly and impositively under control of the operator through pedal P and chain 30 until he obtains proper tension on the various strips before the automatic contact circuit (Fig. 4) is in operation with all contacts J and L open. Then, a further depression of pedal P will cause bell crank 26 to depress push button 33, thus closing switch M to put the machine in its normal running condition under automatic control of a 6-volt circuit from the secondary transformer 34.

Referring to Figs. 1 and 4, it will be clear that with switch M closed and the machine in opera-

tion, if any strip 14 breaks, thereby permitting its bar L to bear against a contact J, relay 35 will be energized and contact plate 36 will break contact 40 to stop motor 39, and will engage contact 37, as shown in broken line in Fig. 4, to close the 110 volt circuit thus activating solenoid 38 and causing brake band E to grip drum D, thus instantly stopping rotation of mandrel 18.

In practice a motor switch 41 is provided, and a micro-switch 42 for a turn counter may be included in the circuit if desired.

What is claimed is:

1. In a web handling apparatus wherein at least one web is wound upon a mandrel and wherein the web is to be maintained under a predetermined tension as it is wound on the mandrel operating at a predetermined speed, the combination for selectively controlling the mandrel speed until the desired tension is obtained and for automatically stopping the mandrel when there is a decrease in the predetermined tension of the web, comprising, a driving shaft, a web receiving mandrel rotated by said shaft, a driving means, clutch means disposed between the mandrel driving shaft and the driving means, operator-controlled means for impositively engaging the clutch for driving the mandrel at selective slow speeds below the predetermined speed, an automatic control switch for closing an automatic control circuit operated by the operator controlled means when the clutch means is fully engaged, the automatic control circuit including a motor circuit for operating the driving means and a braking circuit for stopping the driving shaft, a solenoid switch circuit for selectively and alternately closing the motor and braking circuits and which when closed causes the motor circuit to be opened and the braking circuit to be closed, and switch means for closing the solenoid switch circuit which includes a pair of contact devices one on each side of the web when the latter is under tension, one of the devices being stationary and the other movable, and a gravity device for maintaining the movable contact device in contact with the web, the gravity device being effective to move the movable contact device against the stationary contact device should the tension in the sheet be decreased.

2. In a machine for moving at least one web under predetermined tension, comprising, a mandrel for receiving the web under the predetermined tension, motor means for rotating the mandrel at a normal speed when the web is under the desired tension, automatic means which become operable when the mandrel is operated at said normal speed including means for stopping said motor means whenever the tension fails in said web, and means for applying a brake to said motor means, clutch means disposed between the mandrel and the motor means for connecting the mandrel and the motor means, operator-controlled means for impositively engaging the clutch means to drive the mandrel at selective speeds slower than the normal speed, and for positively engaging the clutch means to drive the mandrel at the said normal speed, switch means for closing the circuit of the automatic means actuated by the operator-controlled means when the latter is moved to positively engage the clutch means.

3. In a motor driven machine for forming about a mandrel a roll from at least one web

under tension when the mandrel is driven at a predetermined speed, the combination, comprising, a mandrel, and mandrel-driving means, motor means, a clutch disposed between the motor means and the mandrel-driving means for positively driving the mandrel at the predetermined speed and for impositively and selectively driving the mandrel at speeds less than the predetermined speed, an automatic control means operable when the mandrel driving means is positively driven by the motor means, the automatic control means including a motor circuit for controlling the motor means and a braking circuit for stopping the mandrel driving means, a solenoid switch circuit for selectively and alternately closing the motor and braking circuits and which when closed causes the motor circuit to be opened and the braking circuit to be closed, tension failure switch means for closing the solenoid switch circuit which includes a pair of contact devices one on each side of the web when the latter is under tension, one of the contact devices being stationary and the other movable, means for maintaining the movable contact device in contact with the web and effective to move the movable contact device against the stationary contact device when the tension in the sheet is decreased.

4. In a motor driven machine for forming about a mandrel a roll from at least one web under tension when the mandrel is driven at a predetermined speed, the combination, comprising, a mandrel, and mandrel-driving means, motor means, a clutch disposed between the motor means and the mandrel-driving means for positively driving the mandrel at the predetermined speed and for impositively and selectively driving the mandrel at speeds less than the predetermined speed, an automatic control means operable when the mandrel driving means is positively driven by the motor means, the automatic control means including a motor circuit for controlling the motor means and a braking circuit for stopping the mandrel driving means, a solenoid switch circuit for selectively and alternately closing the motor and braking circuits and which when closed causes the motor circuit to be opened and the braking circuit to be closed, tension failure switch means for closing the solenoid switch circuit which includes a pair of contact devices, one of said contact devices being movable toward the other contact device and maintained out of contact with said other contact device by means engaging the web under tension, said movable contact device being adapted to engage the other contact device when there is a reduction in tension.
